RIVETING OR STAKING MACHINE

Herman Bloss, Shelton, Conn.

Application March 23, 1944, Serial No. 527,768

15 Claims. (Cl. 78—48)

This invention relates to riveting or staking machines and, more especially, to a tool of this type designed for relatively light work. In the past, machines for performing the work of riveting have been relatively expensive and complicated and there has been a scarcity of such devices suitable for light work upon which satisfactory and efficient riveting or staking can be accomplished.

One object of the present invention is to provide a relatively simple and inexpensive riveting machine which will be efficient in operation.

A further object of the invention is to provide a riveting machine having means for holding the hammer arm in raised position ready for an operative stroke, which means is of novel construction and operation.

A further object of the invention is to provide a riveting machine of the character described, which shall have improved means for bringing about the power stroke of the hammer.

Still another object of the invention is to provide a riveting machine which will have improved means for bringing about the power stroke of the hammer and which will also have improved means for returning the hammer to its original position in readiness for a further operation.

Still another object of the invention is to provide a riveting machine having power means for effecting an operative stroke of the hammer and having power means for effecting a return stroke of the hammer, the latter means so arranged that it will be automatically effective so that once the tool is set in operation the hammer will be brought down upon the tool and will also be returned to its original position where it will be held until a further operation is required.

To these and other ends, the invention relates to the novel features and combinations of parts to be hereinafter described and claimed.

In the accompanying drawings:

Fig. 1 is a side elevational view of a riveting or staking tool embodying my invention, with some parts being shown in section;

Fig. 2 is a sectional view of a riveting or staking tool of modified form; and

Fig. 3 is a view similar to Fig. 2, showing a further modification.

To illustrate a preferred embodiment of my invention, I have shown in Fig. 1 of the drawings a tool comprising a base or bed 10, from which rises an arm 11 carrying a vertically disposed sleeve 12. Within this sleeve is slidably mounted a tool holder 13 to which may be removably secured a proper tool 14. This tool may

be secured to the tool holder by means of the threaded connection shown at 15, so that the tool may be removed to be replaced by a new one or one of a different type. Secured to the tool holder 13 is a pin 16 which is adapted to slide in a slot 17 in sleeve 12, and a spring 18 is connected to the pin 16 and to a pin 19 secured in sleeve 12 to maintain the tool in an elevated position as shown ready for an operative stroke

10 upon the work.

Adjacent the sleeve 12, a buffer or shock absorbing device may be carried by the arm 11. This device may comprise a bolt or pin 20 having a head 21, the body of the bolt passing through 15 the arm or standard 11, and having a nut 22 secured upon its lower end. The standard 11 is provided with a socket 23 within which is seated a spring 24, which spring acts against the bottom of the socket and the head 21 of the 20 bolt to maintain the latter in raised position and to cushion the blow of the hammer when the latter is near the end of its operative stroke.

Secured at the rear end of the standard 11 is a post 25 having an upper bifurcated end 26 between the parts of which is pivoted a hammer arm 27 upon the pivot pin 28, passing through the bifurcated portions of the post. The arm 27 carries at its forward end the hammer 29 which may be of considerable weight compared to the 30 associated parts so that it will drop with considerable gravitational force upon the tool carrier 13. If desired, means such as rubber bands 30 may be employed to assist the operative or downward stroke of the hammer.

35 At its rear end, the hammer arm 27 is provided with a handle 31, by which it may be manually returned to its raised position after having descended upon the tool holder. Also, rearwardly of the pivot 28, the arm 27 is provided 40 with a laterally projecting pin 32 adapted to be received in a notch or recess 33 formed in a latch member 34 when the hammer arm is in raised position as shown in Fig. 1.

The latch member 34 is pivoted to the post 25 45 at 35 and an actuating link 36 is pivoted to the lower end of this member, as at 37. A spring 38 is connected at one end to a pin 39 on the post 25, and at the other end to a pin 40 on the latch member 34, to normally urge the upper end of 50 the latch member toward the left as shown in Fig. 1, or toward its operative position. A stop pin 41 may be provided in the post or standard 25 to limit the movement of the member 34 under the impulse of the spring.

55 Pivoted to the bed 10 at 42 is a trigger or ac-

tuating member 43 which is also pivoted to the link 36 at 44. Supported on the bed 10 is an anvil 45, upon which the work is adapted to rest. The latch member 34 is provided with a cam-shaped upper end 47 designed to be engaged by the pin 32 upon the return or upstroke of the hammer to cam the latch member 34 rearwardly, so that the pin 32 may enter the notch 33.

The operation of my device is as follows. As shown in Fig. 1, the parts are in a position of rest, ready for an operative stroke. The hammer, at this time, is held in its elevated position by the engagement of the pin 32 in the recess 33 of the latch element 34. The operator of the machine may press downwardly on the trigger 43 which rocks the latch element 34 about the pivot 35 and moves the upper end of this member rearwardly so as to disengage the pin 32 from the notch 33. As soon as this disengagement takes place, the hammer descends upon the tool holder 13 either by reason of its own weight or by reason of its weight and the impulse of the rubber bands 30. The tool 14 is thus driven down upon the work which rests on the anvil 45. As the hammer 29 moves toward the bottom of its stroke, it strikes the buffer or shock absorber 21, and its descent is checked by the spring 24.

At this time, the upper end of the latch member 34 will be drawn forwardly against the pin 41 by its spring 38. To return the tool to its original position which is the position shown in Fig. 1, the operator grasps the handle 31 and draws it downwardly, thus raising the hammer and bringing the pin 32 into engagement with the cam surface 47 of the latch element 34 to cam this element rearwardly against the tension of the spring 38 until the pin 32 is opposite the mouth of the notch 33, at which time the latch member 34 springs forwardly to engage the pin 32 and hold the hammer in the position shown.

In Fig. 2 of the drawings, I have shown a modified form of a device in which the operative stroke of the hammer is effected by a power-operated device such as a solenoid, for example. In this instance, the frame of the tool is shown at 50, upon which are a pair of spaced flanges 50^a, only one of which is shown in the drawings and between which much of the operating mechanism is mounted, as will be presently described. A bed 51 is secured to the forward part of the frame which carries the work support or anvil 52. A tool holder 53 and buffer structure 54 are mounted in a forward portion of the frame, and are substantially like the corresponding parts shown in Fig. 1 of the drawings, so that further description of these elements will be unnecessary.

The hammer is shown at 55, the hammer being carried at the forward ends of a pair of spaced arms 56 (only one being shown in the drawings), which arms are pivoted between the flanges 50^a by the pivot pin 57. These arms are also connected by pins 58 and 59, and by plate 60 to which is secured by the adjusting screw 61 a return spring 62, the lower end of which is secured to a pin 63 extending between the flanges 50^a.

The latch member 65, having a disk-like lower end portion 66, is pivoted upon a pin 67 supported by the flanges 50^a, which latch member is provided with a recess or notch 68 adapted to engage the pin 59 when the hammer is in an elevated position, and also provided with an upper cam-shaped end 69 with which the pin 58 engages upon the upstroke of the hammer to cam the latch member rearwardly or toward the right, as shown in Fig. 2.

The latch member 65 is urged against a stop pin 70 by a spring 71 secured at one end to a pin 72 on the latch member, and secured at the other end to the frame 50 as shown at 73.

5 A solenoid 75 may be employed to effect the down stroke of the hammer, the case of which is pivoted to the frame at 76, which solenoid is provided with a plunger 77 pivoted at 78 to the arms 56. As the point 58 moves about the pivot 10 pin 57 during the movements of the hammer, it is desirable to pivot the case of the solenoid at 76 so that it may swing to accommodate itself to the arcuate movement of the pin 58. The solenoid is adapted to be energized through wires 15 78 and 79, one of which leads to a terminal of the coil of the solenoid and the other of which leads to switch contacts 80 and 81 insulated from each other as at 82. The lower ends of these members constitute a switch 83 to complete the 20 circuit when they are brought into contact.

Controlling means are provided for controlling the operation of the device, which means comprise a disk-like member 84 pivoted upon the pin 67 adjacent the part 66 of the latch member 65. This disk-like member has projecting arms 85 and 86. To the latter arm is secured a link 87 leading to a pedal or foot control for the 30 operation of the tool, I also provide a hand control for the trigger 88 pivoted to the bed at 89 and also pivoted at 90 to a link 91 upon which is a pin 92 engaged in an elongated slot 93 in the arm 85. It will be noted that the link 91 is outside and 35 not between the flanges 50^a, so that the pin 92 must extend through one of these flanges which is provided with a slot 94 for this purpose. Also, the arm 85 is provided with a forwardly projecting member 97 designed to engage the lower ends of the contact members 80 and 81 and force them 40 together to close the switch 83, and complete the circuit through the solenoid.

It may be noted that the disk 84 is provided with elongated arcuate slots 98, within which lie pins 99 secured to the disk-like member 66, so 45 that the members 66 and 84 are connected by a lost motion connection, allowing independent movement between these parts in one direction. It will also be apparent that, when either the link 50 87 leading to the foot control or when the hand control member 88 is operated downwardly, the arm 85 will be moved toward the left as shown in Fig. 2, thus closing the switch 83 and also 55 swinging the latch member 65 in a clockwise direction. When the controls are released, the arm 85 will be restored to its original position by the spring 100 secured at one end to the arm 85 and at the other end to the flange 50^a.

As shown in Fig. 2, the hammer is at the bottom of its stroke and it will be assumed that the controls have been released so that the springs 60 71 and 100 have returned the latch member 65 and the disk 84 to the positions shown. The switch 83 is therefore open and the solenoid de- 65 energized. The spring 62 will therefore return the hammer to its elevated position. During this movement, the pin 59 acting on the cam surface 69 will cam the latch member 65 in a clockwise direction to permit the pin 58 to enter the slot 68. During this movement of the latch member 65, the arm 85 will remain stationary as independent movement of the arm 85 will be permitted by movement of the pins 99 in the slots 98 so that the latch member 65 may move to a sufficient extent in a clockwise direction to permit 70 the pin 58 to enter notch 68 without any move- 75

ment of the disk 84. Thereafter, the spring 71 will return the latch member 65 to its position against the stop pin 70, at which time the hammer will be held in its elevated position ready for a further operation.

With the hammer so held, the operator may actuate the manual hand control 88 or the foot lever 87, thus rotating the disk-like member 84 and swinging the latch member 65 in a clockwise direction to release pin 59. At the same time, the arm 85 is moved to the left to close the circuit through the switch 83 and energize the solenoid which effects an operative downward stroke of the hammer against the tool holder 53 in opposition to the tension of the spring 62. Upon release of the control members, the arm 85 is moved rearwardly by the spring 100 which opens the switch 83 and permits the return spring 62 to elevate the hammer.

In Fig. 3 of the drawings, I have shown a further modification of my device which is quite similar to that shown in Fig. 2 except that the return stroke of the hammer is also effected by a solenoid instead of by means of a spring. In this case, the frame of the machine is shown at 50, having flanges 50a between which the principal operating parts of the device are mounted. The hammer 55, hammer arms 56, pivots 57 and 58, and the solenoid 75, pivoted at 76, are similar to the corresponding parts previously described in connection with the structure shown in Fig. 2.

The arms 56 may be provided with additional openings 102 for reception of the pin 58 to permit adjustment of the hammer stroke by adjusting the point of connection of the plunger 71 of the solenoid to the arms.

At their rear ends, the arms are provided with a pin 59 designed to cooperate with a latch member 65 similar to that previously described, this member being pivoted at 67 to the frame of the machine and also having a slot and pin connection 98 and 99 with the control member 84, which carries an arm 85 designed to be operated by the hand control member 88.

Also connected to the pin 59 is a link 104 secured by a turnbuckle 105 to the plunger 106 of a second solenoid 107, the case of which is pivoted to the frame at 108, which solenoid, it will be understood, operates to effect a return stroke of the hammer.

Current may be delivered to the solenoids 75 and 107 by the lead wires 109 and 110, which wires are connected to the solenoid 75 through the switch 111 and to the solenoid 107 through the switch 112. The arm 85, connected to the disk 84, is provided with switch-operating projections 113 and 114, so that, when this arm is moved in one direction, it will close the circuit through the switch 111, and when moved in the other direction it will close the circuit through the switch 112, the arm being held in the position shown in Fig. 3 by the spring 115. It will be understood that in this instance the pins 99 are secured to the disk 84 and the slots 98 are in the lower disk-shaped end of the latch member 65.

At the lower end of the latch member 65 is a cutout arm 116, which arm serves to open the circuit through the switch 112, as will be explained hereinafter.

The hammer is shown in its raised position in Fig. 3 of the drawings, ready for an operative stroke. If the operator moves the hand control 88 downwardly, the latch member 65 will be moved in a counterclockwise direction and release the pin 59. At the same time, the member 75

114 will close the circuit through switch 111 and energize the solenoid 75 which will bring the hammer downwardly against the tool holder. As soon as the control member 88 is released, the spring 115 will restore the arm 85 to the position shown in Fig. 3, thus opening the switch 111 to de-energize the solenoid 75 and closing the switch 112 to energize the solenoid 107, and thus effect a return stroke of the hammer. During this stroke, the pin 59 will engage the cam surface 69 of the latch member 65 and cam it rearwardly to permit the pin 59 to pass into the notch 68, which movement of the latch member 65 will be permitted by the lost motion engagement of the slots 98 with the pins 99. The device is now in readiness for a subsequent operation.

It will be understood that the switches 111 and 112 (and also switch 83) comprise spring contact members biased to stand normally in open position. When the arm 85 is in the position shown in Fig. 3, the switch 112 would be closed by the member 113 were it not for the fact that it is held open by the cutout arm 116 on the latch member which holds the switch open when the notch in latch member engages the pin 59 as it does when the parts are at rest. However, when after an operative stroke the arm 85 is returned to the position shown by its spring 115, the upper cam end of the latch member is engaged by the pin 59 and the cutout arm is held out of engagement with the switch, thus permitting the latter to be closed by member 113. As soon as the notch in the latch member slips over the pin 59, the cutout arm opens the switch.

While I have shown and described some preferred embodiments of my invention, it will be understood that it is not to be limited to all of the details shown but is capable of modification and variation within the spirit of the invention and within the scope of the claims.

What I claim is:

1. A machine of the class described, comprising a reciprocably mounted tool holder, a hammer adapted to strike said tool holder upon its descent, a pivotally-mounted arm carrying said hammer, a movable latch member adapted to engage a part of said arm and hold the hammer in elevated position, spring means to urge said latch member toward engaging position, said member having a cam-shaped surface to be engaged and moved by said part on the arm when the hammer is raised, and means for actuating the latch member to effect disengagement thereof from said part.

2. A machine of the class described, comprising a reciprocably mounted tool holder, a hammer adapted to strike said tool holder upon its descent, a pivotally-mounted arm carrying said hammer, a movable latch member adapted to engage a part of said arm and hold the hammer in elevated position, spring means to urge said latch member toward engaging position, said member having a cam-shaped surface to be engaged and moved by said part on the arm when the hammer is raised, means for actuating the latch member to effect disengagement thereof from said part, spring means to effect the raising of the hammer, and means to effect a down stroke thereof against the action of said last-named spring means.

3. A machine of the class described, comprising a reciprocably mounted tool holder, a hammer adapted to strike said tool holder upon its descent, a pivotally-mounted arm carrying said hammer, a movable latch member adapted to engage a part of said arm and hold the hammer in elevated position, spring means to urge said latch member

toward engaging position, said member having a cam-shaped surface to be engaged and moved by said part on the arm when the hammer is raised, means for actuating the latch member to effect disengagement thereof from said part, spring means to effect the raising of the hammer, and a solenoid to effect the down stroke thereof against the action of said last-named spring means.

4. A machine of the class described, comprising a reciprocably mounted tool holder, a hammer adapted to strike said tool holder upon its descent, a pivotally-mounted arm carrying said hammer, a movable latch member adapted to engage a part of said arm and hold the hammer in elevated position, spring means to urge said latch member toward engaging position, said member having a cam-shaped surface to be engaged and moved by said part on the arm when the hammer is raised, means for actuating the latch member to effect disengagement thereof from said part, spring means to effect the raising of the hammer, and a pivotally mounted solenoid to effect the down stroke thereof against the action of said last-named spring means.

5. A riveting or like machine, comprising a frame, a pivotally-mounted hammer, power-operated means for effecting an operative stroke of the hammer including a plunger pivoted to the hammer, and a member pivoted to the frame cooperating with said plunger.

6. A riveting or like tool, comprising a frame, a hammer pivotally mounted on the frame, a solenoid, a plunger actuated by the solenoid and connected to the hammer to effect an operative stroke thereof, latching means to hold said hammer in raised position, and a control member operative to release said latching means and energize said solenoid.

7. A riveting or like tool, comprising a frame, a hammer pivotally mounted on the frame, a solenoid, a plunger actuated by the solenoid and connected to the hammer to effect an operative stroke thereof, latching means to hold said hammer in raised position, a control member operative to release said latching means and energize said solenoid, and means to effect a return movement of said hammer upon release of said control means.

8. A riveting or like tool, comprising a frame, a hammer pivotally mounted on the frame, a solenoid, a plunger actuated by the solenoid and connected to the hammer to effect an operative stroke thereof, latching means to hold said hammer in raised position, a control member operative to release said latching means and energize said solenoid, and means to effect a return movement of said hammer upon release of said control means, said last-named means comprising a spring connected to said hammer on the side of its pivot opposite the plunger connection.

9. A riveting or like tool, comprising a frame, a hammer pivotally mounted on the frame, a solenoid, a plunger actuated by the solenoid and connected to the hammer to effect an operative stroke thereof, latching means to hold said hammer in raised position, a control member operative to release said latching means and energize said solenoid, and means to effect a return movement of said hammer upon release of said control means, said last-named means comprising a second solenoid having a plunger connected to said hammer.

10. A riveting or like tool, comprising a frame, a hammer pivotally mounted on the frame, a

solenoid, a plunger actuated by the solenoid and connected to the hammer to effect an operative stroke thereof, latching means to hold said hammer in raised position, a control member operative to release said latching means and energize said solenoid, means to effect a return movement of said hammer upon release of said control means, said last-named means comprising a second solenoid having a plunger connected to said hammer, said control member having an oscillatory movement, and switch means for said solenoids actuated alternately by said control member upon oscillation thereof.

11. A riveting or like tool, comprising a frame, a hammer pivotally mounted on the frame, a solenoid, a plunger actuated by the solenoid and connected to the hammer to effect an operative stroke thereof, latching means to hold said hammer in raised position, and a control member operative to release said latching means and energize said solenoid, said latching means comprising a pivoted member engaging a part of said arm and said control member having a lost motion connection with said member.

12. A riveting or like tool, comprising a frame, a hammer pivotally mounted on the frame, a solenoid, a plunger actuated by the solenoid and connected to the hammer to effect an operative stroke thereof, latching means to hold said hammer in raised position, and a control member operative to release said latching means and energize said solenoid, said latching means comprising a pivot member having a cam-shaped end and a recess, said hammer having a part adapted to engage said end and to be engaged in said recess, and said control member being pivoted coaxially with said first pivoted member and having a lost motion connection therewith.

13. A machine of the class described, comprising a reciprocably mounted tool holder, a hammer adapted to strike said tool holder upon its descent, a pivotally-mounted arm carrying said hammer, a movable latch member adapted to engage a part of said arm and hold the hammer in elevated position, spring means to urge said latch member toward engaging position, said member having a cam-shaped surface to be engaged and moved by said part on the arm when the hammer is raised, a control arm pivoted adjacent said latch member and having a lost motion connection therewith, electrically operating means for effecting an operative stroke of the hammer, and said control arm when actuated in one direction serving to disengage said latch member from said hammer and close said switch.

14. A machine of the class described, comprising a reciprocably mounted tool holder, a hammer adapted to strike said tool holder upon its descent, a pivotally-mounted arm carrying said hammer, a movable latch member adapted to engage a part of said arm and hold the hammer in elevated position, spring means to urge said latch member toward engaging position, said member having a cam-shaped surface to be engaged and moved by said part on the arm when the hammer is raised, a manually actuated member pivoted adjacent said latch member and having a lost motion connection therewith, power means to effect an operative stroke of the hammer, power means to effect a return stroke of the hammer, and a control device for each of said power means, said devices being disposed on opposite sides of said manually actu-

ated member whereby said member actuates one of said control devices and moves it in one direction and the other thereof when moved in the other direction.

15. A riveting or like tool, comprising a frame, a hammer pivotally mounted on the frame, a plunger connected to said hammer, power-op-

erated means to effect movement of said plunger to bring about an operative stroke of the hammer, latching means to hold said hammer in raised position, and a control member operative to release said latching means and to energize said power-operated means.

HERMAN BLOSS.
